LOCOMOTIVE TENDER

Edwin Archer Turner, New York, N. Y., assignor
to The Standard Stoker Company, Incorporated,
a corporation of Delaware

Application May 5, 1931, Serial No. 535,127

24 Claims. (Cl. 105—231)

This invention relates to improvements in locomotive tenders and has for its principal object to produce a new and improved construction wherein the tender is in the form of an integral skeleton frame casting of sufficient strength to provide in effect a main frame structure, the open portions of said casting being thereafter finished by welding in or riveting in relatively thin metal sheets to complete the tender structure.

Other and more specific objects of the invention reside in the construction and arrangement of the parts hereinafter fully described and set forth in the appended claims.

In the accompanying drawings

Fig. 1 is a side view of the improved tender construction;

Fig. 2 is a vertical sectional view on the line 2—2 of Fig. 3;

Fig. 3 is a plan view of the tender construction;

Fig. 4 is a sectional plan view on the line 4—4 of Fig. 2;

Fig. 5 is a sectional view at the front end of the tender on the line 5—5 of Fig. 1;

Fig. 6 is a transverse sectional view on the line 6—6 of Fig. 1;

Fig. 7 is a transverse sectional view similar to Fig. 5 showing a modified form of the invention in which the stoker trough housing is illustrated;

Fig. 8 is a horizontal section taken on the line 8—8 of Fig. 7;

Fig. 9 is a front view of a portion of the tender body of the form shown in Figs. 7 and 8;

Fig. 10 is a transverse sectional view similar to Fig. 5 showing another modification of the invention;

Fig. 11 is a horizontal section taken on the line 11—11 of Fig. 10; and

Fig. 12 is a fragmentary transverse section through the forward end of the tender showing a modified form of the invention illustrated in Figures 10 and 11.

Referring to the drawings, particularly Figures 1 to 6, inclusive, the integral skeleton tender frame casting is represented generally by the numeral 10, and comprises the base 11, having a central longitudinal beam 12, preferably of the box type, rectangular in cross section. Extending horizontally from each side of the beam 12 are the base plates 13 of the tender. These base plates extend to the sides of the tender and connect with the integrally formed cored sidewalls 14 and 15. The cored front wall 16 and cored rear wall 17 of the tender are formed integral

with the ends of the base 11 and connect with and are formed integral with the cored sidewalls 14 and 15. In other words, the skeleton framework of the tender body is formed by the upstanding spaced ribs 14a, 15a cast integrally with the base plate 13 along the sides of the tender body, and the upstanding spaced ribs 17a cast integrally with the base plate 13 along the ends of the tender body. At each corner of the body and cast to the base plate 13 are the upstanding ribs r which are curved in horizontal cross section and are provided with flat portions at each side of the curved portion. By this construction, flat steel plates can be secured to the ribs 14a, 15a, 17a and the flat portions of the curved ribs r, thereby making it unnecessary to form expensive dies for flanging the steel plates, which was necessary in tender constructions prior to this invention. To insure rigidity, the ribs 14a, 15a and r may be joined by the longitudinal ties webs w.

The cored side slope sheets 18 and 19 and the cored rear slope sheet 20 are formed as an integral part of the tender skeleton frame 10 and divide the fuel and water compartments 21 and 22 respectively. The bottom of the fuel compartment 21 is formed by the stoker conveyor trough frame 23 constituting an integral extension of the cored side slope sheets 18 and 19 and the cored rear slope sheet 20. Integrally formed transverse members 24 support the trough 23 from the top plate 25 of the beam 12.

Formed integral with the trough frame 23 and extending longitudinally thereof is the stoker drive shaft housing 26. The trough frame 23 and stoker drive shaft housing 26 are apertured at 27 and 28 respectively, opening through the tender front wall 16 to receive a conveyor screw (not shown) and drive shaft (not shown) respectively. At their rearward ends the trough 23 and housing 26 are apertured at 29 and 30 respectively, opening into a skeleton gear housing compartment 31 which is formed as an integral part of the tender structure.

The skeleton gear housing compartment 31 is formed by the front wall 32, constituting a downward extension of the rear slope sheet 20, the cored rear wall 33, cored sidewalls 34 and 35 and cored top wall 36. The bottom of the gear housing compartment 31 is provided with an opening 37 extending through the tender underframe, permitting ready access to the trough gearing (not shown) for purposes of installation or repair.

Transverse baffle plates or tie members 38 to restrain the surging back and forth and excessive

60

110

movement of the water are formed as an integral part of the tender structure and are provided with the apertures 39. Each tie member 38 is cast to a rib along one side of the tender body and to a corresponding rib along the opposite side. At their upper and lower ends, the tie members 38 are cast to the roof 40 and the base 13 respectively. Cast to each of the ribs 17a are the longitudinal tie members such as 75 which are cast 10 to the tie members or plates 38 forming pillars or posts 76 which at their lower ends are cast to the base 13.

The roof 40 of the tender is formed as an integral part of the tender structure and like the 15 side and end walls comprises a plurality of intersecting cast ribs 40a to form a skeleton framework.

The open portions of the tender skeleton casting where desired are closed by metal plates, 20 preferably sheets of steel, shown conventionally in the figures by the letter *p*, which are welded or riveted in place to complete the tender structure and made water tight.

In Figures 7, 8 and 9 is illustrated a modified 25 form of the invention in which a housing framework 41 for the stoker trough and stoker drive shaft (not shown) is provided. The housing framework 41 is formed as an integral part of the tender structure, and comprises the floor 42 30 formed by the top plate 25 of the beam 12 and the integral extensions 43 and 44 on each side thereof; the cored sidewalls 45 and 46, constituting downward extensions of the side slope sheets 18 and 19, the front wall 47 and the rear 35 wall 48 constituting a downward extension of the rear slope sheet.

Laterally directed cored ledges 49 and 50 extend inwardly from the juncture of the side slope sheets 18 and 19 and the housing sidewalls 45 and 46, and are formed integral therewith. The ledges 49 and 50 form a floor portion for the fuel compartment 21 and top wall portion for the housing 41. The trough is formed as an integral extension of the ledges 49 and 50. The open portions of the housing 41 are closed by metal plates *p* which are welded or riveted in place forming a water tight compartment through which extends the stoker drive shaft (not shown) longitudinally of the stoker trough. Where it is desired to have 45 a water tight drive shaft housing integral with the trough as shown at 26 in Figures 1 to 6, it is only necessary to close the open forward portions of the stoker trough housing 41.

In Figures 10 and 11 is shown a modification of 50 the construction illustrated in Figures 7, 8 and 9, in which a separable trough 51 is provided. In this form of the invention the laterally inwardly directed ledges 49 and 50 are provided with the grooves 52 and 53 forming a seat for the trough 51. The trough 51 is provided with an integrally formed front transverse wall 54 which extends laterally beyond the sidewalls of the trough immediately forward of the tender front wall 16 to form a flange-like extension overlapping the U-shaped seat or opening 55 in the wall 16. The front transverse wall 54 is apertured at 56 to receive a conveyor screw for advancing fuel through the trough. A drive shaft housing 57 for protecting the stoker drive shaft 55 from the water is cast integral with a sidewall of the trough 51 extending lengthwise thereof and opening at its forward end through the transverse wall 54.

By welding the marginal edges of the trough 51 and drive shaft housing 57 adjacent their

rearward open ends 58 and 59 respectively, with the wall 32 a durable structure and a water tight connection is obtained. Likewise the marginal edges of the transverse front wall 54 are welded with the tender front wall 16, and the laterally extending flanges 60 and 61 of the trough 51 are welded in the grooves 52 and 53 of the ledges 49 and 50 forming water tight connections. In this form of the invention the space immediately beneath the trough 51 and within the housing 41 may be used as additional water space. The cored sidewalls 45 and 46 of the housing 41 permit circulation of water from the water compartment through the housing 41.

Figure 12 shows a modification of the form of the invention illustrated in Figures 10 and 11, in which the cored sidewalls 45 and 46 of the housing 41 are closed by welding or riveting of thin metal plates *p* over the apertured portions forming a water tight construction. The stoker drive shaft (not shown) extends through the housing 41 and need not be provided with a drive shaft housing 57 described in connection with Figures 10 and 11.

I claim:

1. A locomotive tender body in the form of an integral skeleton casting comprising a base, a plurality of upstanding spaced ribs cast along the sides of the tender body, and tie members or plates extending transversely of the tender, each tie member cast to a rib along one side of the tender body and to a corresponding rib along the opposite side.

2. A locomotive tender body in the form of an integral skeleton casting comprising a base, a plurality of upstanding spaced ribs cast along the sides and ends of the tender body, and tie members or plates extending transversely of the tender, each tie member cast to a rib along one side of the tender body and to a corresponding rib 115 along the opposite side.

3. A locomotive tender body in the form of an integral skeleton casting comprising a base, a plurality of upstanding spaced ribs cast along the sides of the tender body, a plurality of upstanding spaced ribs cast along an end of the tender body, tie members or plates extending transversely of the tender, each tie member cast to a rib along one side of the tender body and to a corresponding rib along the opposite side, and tie members or plates extending longitudinally of the tender, each of said tie members being cast to a respective rib along an end of the tender body and to at least one of said first named tie members.

4. A locomotive tender body in the form of an integral skeleton casting comprising a base, a plurality of upstanding spaced ribs cast along the sides of the tender body, tie members or plates extending transversely of the tender, each tie member cast to a rib along one side of the tender body and to a corresponding rib along the opposite side, and apertured side and rear slope sheets cast to the tender body and dividing it into fuel and water compartments.

5. A locomotive tender body in the form of an integral skeleton casting comprising a base, a plurality of upstanding spaced ribs cast along the sides of the tender body, tie members or plates extending transversely of the tender, each tie member cast to a rib along one side of the tender and to a corresponding rib along the opposite side, apertured side and rear slope sheets cast to the tender body and dividing it into fuel and water compartments, and a trough adjacent the

- lower marginal edges of said slope sheets forming the bottom of the fuel compartment.
6. A locomotive tender body in the form of an integral skeleton casting comprising a base, a plurality of upstanding spaced ribs cast along the sides of the tender body, tie members or plates extending transversely of the tender, each tie member cast to a rib along one side of the tender and to a corresponding rib along the opposite side, apertured side and rear slope sheets cast to the tender body and dividing it into fuel and water compartments, a trough adjacent the lower marginal edges of said slope sheets forming the bottom of the fuel compartment, and a skeleton compartment frame rearward of said trough for housing stoker drive mechanism. 80
7. A locomotive tender body in the form of an integral skeleton casting comprising a base, a plurality of upstanding spaced ribs cast along the sides of the tender body, tie members or plates extending transversely of the tender, each tie member cast to a rib along one side of the tender and to a corresponding rib along the opposite side, apertured side and rear slope sheets cast to the tender body and dividing it into fuel and water compartments, a trough adjacent the lower marginal edges of said slope sheets forming the bottom of the fuel compartment, a skeleton compartment frame rearward of said trough for housing stoker drive gears, and a stoker conveyor drive shaft housing cast to said trough and extending longitudinally thereof 90

slope sheets having laterally and inwardly extending flanges adapted to receive a conveyor trough.

16. A locomotive tender body comprising in an integral casting a base, a plurality of upstanding spaced ribs cast along the sides and ends of said base, and a conveyor trough housing framework cast to said base and including apertured sidewalls, said sidewalls at their top portions having laterally and inwardly extending flanges adapted to receive a conveyor trough.

17. A locomotive tender body comprising in an integral casting a base, and a conveyor trough housing framework cast to said base and including apertured sidewalls, said sidewalls at their top portions having laterally and inwardly extending flanges adapted to receive a conveyor trough.

18. A locomotive tender body comprising in an integral casting a base, a plurality of upstanding spaced ribs cast along the sides and ends of said base, an apertured rear slope sheet and apertured side slope sheets cast to said tender body dividing it into fuel and water compartments, a conveyor trough housing framework cast to said base and including apertured sidewalls, said sidewalls constituting downward extensions of said side slope sheets, and laterally and inwardly extending flanges at the juncture of said sidewalls and said side slope sheets adapted to receive a conveyor trough.

19. A locomotive tender body comprising in an integral casting a base, an apertured rear slope sheet and apertured side slope sheets cast to said tender body dividing it into fuel and water compartments, a conveyor trough housing framework cast to said base and including apertured sidewalls, said sidewalls constituting downward extensions of said side slope sheets, and laterally and inwardly extending flanges at the juncture of said sidewalls and said side slope sheets adapted to receive a conveyor trough.

20. A locomotive tender body comprising a base, a plurality of upstanding spaced ribs cast along the sides and ends of said base, apertured side and rear slope sheets cast to said tender body dividing it into fuel and water compartments, a plurality of intersecting ribs cast to the upper portions of said upstanding ribs forming a skeleton roof for said water compartment, and flat plates secured to said upstanding ribs, said apertured slope sheets and said intersecting ribs.

21. A tender of the class described comprising a rectangular base, an upstanding rib cast to each corner of said rectangular base, upstanding

spaced ribs cast along the sides and ends of said base intermediate said corner ribs, apertured side and rear slope sheets dividing the tender into fuel and water compartments, a stoker conveyor trough frame formed integrally with said tender adjacent the lower marginal edges of said slope sheet, flat plates secured to the ribs along the sides and ends of said tender, flat plates secured to the slope sheets over the apertures therein, and a trough sheet secured to said conveyor trough frame forming a water tight seal between said fuel and water compartments.

22. A tender of the class described comprising a rectangular base, an upstanding rib cast to each corner of said rectangular base, upstanding ribs cast along the sides and ends of said base intermediate said corner ribs, apertured side and rear slope sheets dividing the tender into fuel and water compartments, a trough housing frame cast with said base below said slope sheets, a stoker trough frame formed integrally with the lower marginal edges of said slope sheets and extending into said frame housing, flat plates secured to the ribs along the sides and ends of said tender, flat plates secured to the slope sheets over the apertures therein, flat sheets secured to said trough housing frame forming a water tight seal between said trough housing frame and the water compartment, and a trough sheet secured to said conveyor trough frame forming the bottom of said fuel compartment.

23. A locomotive tender in the form of an integral skeleton casting comprising a rectangular base, an upstanding rib cast to each corner of said rectangular base, each of said ribs when considered in horizontal cross section having a curved portion and flat portions, upstanding spaced flat ribs cast along the sides of said base intermediate said corner ribs, and flat plates secured to the flat portions of said corner ribs and the intermediate ribs forming side and end walls of said tender.

24. A locomotive tender in the form of an integral skeleton casting comprising a rectangular base, an upstanding rib cast to each corner of said rectangular base, each of said ribs when considered in horizontal cross section having a curved portion and flat portions, upstanding spaced flat ribs cast along the sides and ends of said base intermediate said corner ribs, and flat plates secured to the flat portions of said corner ribs and the intermediate ribs forming side and end walls of said tender.

E. ARCHER TURNER.
